HEATING APPARATUS PROVIDED WITH
OVENS

Nils August Ivan Hallström, Stockholm, Sweden,
assignor to Svenska Aktiebolaget Gasaccumulator,
Stockholm, Sweden, a corporation of
Sweden.

Application December 13, 1938, Serial No. 245,496
In Sweden December 14, 1937

4 Claims. (Cl. 126—1)

My invention relates to improvements in heating apparatus such as cooking stoves provided with ovens. More specially the invention relates to apparatus of this kind in which heat is transmitted from a heat generator to the ovens by means of air or other gas circulating in one or more closed circuits and has for its purpose to provide for a high circulation speed of the air or gas and as a consequence thereof a high heat transmission. This is obtained by conveying the air or gas in such a way as to prevent, at least to a certain extent, the temperature of the air or gas from being decreased when flowing upwards. Apparatus of this kind hitherto known are usually provided with a circulation channel, surrounding the ovens and branching off between them. In this way vertical circulation channels, closed at the sides, and of the height of one oven only, have been obtained one above the other, and the temperature of the air ascending in the upper of these channels is decreased by cooled air coming in from the space between the ovens. The difference in pressure in the channel has then been too low to produce sufficiently high circulation speed through thermo-circulation only. It has therefore been suggested to place the ovens close to each other, so as to obtain continuous vertical circulation channels, closed at the sides, and of a height equal to the total height of all the ovens. Through this arrangement, high circulation speed has been attained but the bottoms and tops of the ovens, which touch each other, have not received sufficient heat. In order to overcome this disadvantage it has been suggested to convey the circulating gas through perforations in the bottoms and tops of the ovens. In this way, however, too great resistance to circulation is produced, which will also be dependent upon the size of the objects contained in the ovens.

One object of the invention is to avoid these disadvantages. This result is accomplished by the provision of a circulation channel having a vertical leg which is closed at the sides and of a height equal to the total height of at least two ovens placed one above the other, combined with heat transmitting members, so arranged as to transmit heat from the circulating gas to between the vertically adjacent ovens.

If the ovens are placed at the side of the heat generator the air or other gas ascending in the space between the ovens and the heat generator is cooled by the ovens. This also decreases the draught in the circulation channel. One object of the invention is to increase the circulation

speed in this case by one or more baffles or the like arranged between the ovens and the heat generator in such a way as to prevent the circulating gas from passing therebetween, while heat is transmitted through radiation or conduction to the walls of the ovens which are situated next to the heat generator.

Other objects of the invention will be understood from the following description and the accompanying drawing, forming part of this specification, and in which:

Fig. 1 is a more or less diagrammatic view of one embodiment of my invention;

Fig. 2 is a similar view of another embodiment;

Fig. 3 is a similar view of a third embodiment; and

Fig. 4 is a cross-sectional view of a complete stove showing a fourth embodiment in my invention.

Referring more particularly to Fig. 1 reference character 10 indicates the heat generator of a heating apparatus, provided with two ovens 12 and 14, placed one above the other. These 25 ovens as well as the heat generator are enclosed in a closed chamber, containing air, and extend from the front to the rear wall of said chamber, a circulation channel thus being formed round the two ovens. This channel consists of a vertical section 18, one horizontal section 20, running above the top oven, another vertical section 22, and one horizontal section 24, running below the bottom oven.

When the air in the channel section 18 is 35 heated by the heat generator 10, an ascending air current is produced in this channel. The air, contained in the channel section 22, is cooler, and tends to flow downwards. For this reason the air in the circulation channel is made to 40 circulate in a closed circuit round the ovens.

In order to make sure that a sufficiently large quantity of heat is transmitted to the bottom of the upper oven and the roof of the lower oven, two plates 28 and 30, bent in angles, are arranged 45 between the ovens. The plates have vertical portions running parallel with the heat generator, absorbing heat from same, which is then transmitted to the ovens through the horizontal portions of the plates, which are placed between the ovens. The plates are made of a metal of high heat conductivity, for instance aluminum.

Fig. 2 shows an arrangement, by means of which the increased circulation speed is reached, although there is a channel 26 between the ovens. 50 The channel 18 is in this case closed at the oven

side through a wall 32, running from the lower oven upwards between the heat generator 10 and the upper oven 14. The wall 32 is situated at some distance from the upper oven 14, so that a vertical channel 34, communicating with channel 26, is formed between these parts. One portion of the ascending air column in the channel 18 continues as usual through the channels 20, 22 and 24, whereas one portion flows downwards through the channel 34 and further through the channel 26 to the vertical channel 22. This latter air current transmits heat to the bottom and the side of the oven 14, which faces the heat generator, and to the top of the lower oven 12. The side of the oven 12, which faces the heat generator, receives heat mainly through radiation.

Fig. 3 shows a heating device, the heat generator 10 of which consists of an electric heating element, above which three ovens 12, 14 and 14' are arranged, the one above the other, so that a continuous, vertical channel 18, closed at the sides, is formed at one side of the ovens, a similar channel 22 being formed at the other side of same. The channels 18 and 22 are connected by means of a channel 20. A wall 32' extends downwardly from the right side wall of the oven 12, so that a chamber is formed, containing the heating element, and at the top communicating with the channel 18. The air column, which is heated in this chamber, flows upwards through the channel 18, from where it flows round all ovens and finally returns to the chamber. The air current, circulating in this way, transmits heat from the element to the oven walls, partly directly and partly indirectly through heat conductors 36, which are arranged between the ovens. These heat conductors are provided with flanges 38, by means of which heat is absorbed from the circulating air. The heat, absorbed by the flanges, is conveyed to the roof of the lower oven, the roof and bottom of the middle oven, and to the bottom of the top oven. The other oven walls are swept by the circulating air and receive heat directly from same.

With the latter embodiment of the invention continuous channels 18 and 22, closed at the sides, and of a height equal to the total height of three ovens, are obtained. A substantial pressure, acting in upward direction upon the air column in the channel 18, is produced, so that a rapid circulation, and consequently an efficient transmission of heat takes place.

In Fig. 4 the exterior cover of a stove to which the invention is applied is designated by 110. The heating unit 112 is at its top provided with a cooking plate 114, and is connected to a chimney through a flue 116. The top part of the heating unit as well as the flue are protected against heat losses by insulation 118. The heating unit extends into a chamber 120, filled with air, and insulated against heat losses, in which two ovens 122 and 124 are placed. The ovens extend from the front side to the rear side of the chamber, so that a circulation channel for the air is formed, in one vertical leg of which the heating unit 112 is located. A baffle member 126, also running from the front to the rear side of the air chamber, is arranged between the heating unit and the ovens in such a way as to prevent the air current from ascending between these parts. The air surrounding the heating unit is heated to a high temperature, whereas the air above, below and at the right side of the ovens is cooled by heat transmission to the ovens. The

air surrounding the heating unit then tends to flow upwards, whereas the air in the vertical channel at the right side of the ovens tends to flow downwards. In this way an air current is obtained, moving in a closed circuit passing the heating unit, above the ovens, flowing downwards at the right side of same and below the ovens. When circulating in this way, the air absorbs heat from the heating unit walls, transmits heat to the top of the upper oven, the right side walls of both ovens and to the bottom of the lower oven.

Heat is transmitted through radiation or conduction to the sides of the ovens, which faces the heating unit. For this purpose two U-shaped plates 128 and 130, made from a highly heat conductive metal, for instance aluminum, are arranged between the ovens. The left hand vertical parts of the plates extend parallel to the side wall of the heating unit, from which heat is radiated to the plates. To the bottom of the top oven and to the upper wall of the lower oven heat is conducted through the plates, which also absorb heat from the circulating air through flanges 132 on the right hand parts of the U-shaped plates. The last mentioned parts of the plates 128 and 130 and the parts of same which are situated between the ovens touch the oven walls, whereas the parts of the plates, which face the heating unit, are situated at some distance from the oven walls, so that spaces 134 and 136 are formed between the plates and the ovens. The purpose of these spaces is to prevent the side walls of the ovens, which face the heating unit, from being too highly heated. The spaces 134 and 136 may be filled with insulating material or replaced by an insulating lining on the inner sides of the ovens.

The circulating air is guided by the baffle 126, so as to make it flow round the whole heating unit with the exception of the side of same which faces the oven, and from which heat is radiated to the oven. The heating unit will therefore be uniformly cooled. As the air current in the ascending part of the circulation channel is not cooled through contact with the oven, it reaches a high temperature. The force acting upon the air column in this part of the channel in upward direction will consequently be strong and a rapid circulation takes place.

The arrangement described above may be varied in many different ways within the scope of the invention. Any kind of baffles may be chosen and inserted in such a way as to prevent the air from passing, to a considerable extent, between the heating unit and the ovens. It is also unessential how many ovens are arranged at the side of the heating unit. It is thus possible to employ one oven only, or more than two ovens. The ovens may also be arranged not only at one side of the heating unit, but also at two opposite sides of same, in which case the baffles direct the air current towards the sides of the heating unit, which do not face the ovens.

In the first place, the invention is intended to be used in connection with stoves, but may also be applied to any kind of heating apparatus, provided with ovens. In addition to the examples referred to above, even other embodiments of invention may be possible. The air pressure in the circulation channel should preferably be atmospheric, but higher pressure may also be allowed. It is also possible to replace the air by another gas or gas mixture, for instance combustion gases.

What I claim is:

1. In a heating apparatus, a source of heat, a plurality of ovens disposed vertically with respect to each other, means forming a channel for the circulation of fluid in a closed circuit around said ovens and in heat exchange relation with said source of heat, said channel including a vertically extending leg arranged for upward flow therethrough of fluid heated by said source of heat, said leg being closed except at the upper and lower ends thereof, and means for conducting heat from the fluid flowing through said leg to top and bottom surfaces of said ovens which are adjacent to each other.
2. In a heating apparatus, a source of heat, a plurality of ovens disposed vertically with respect to each other, means forming a channel for the circulation of fluid in a closed circuit around said ovens and in heat exchange relation with said source of heat, said channel including a vertically extending leg arranged for upward flow therethrough of fluid heated by said source of heat, said leg being closed except at the upper and lower ends thereof, and a heat conducting element having a portion disposed between and in heat exchange relation with adjacent top and bottom surfaces of said ovens and having another portion formed with heat transfer surface
3. In a heating apparatus, a source of heat, an oven disposed to one side of said source of heat, means forming a channel for the circulation of fluid in a closed circuit around said oven and in heat exchange relation with said source of heat, said channel including a vertically extending leg in heat exchange relation with said source of heat and remote from said oven, and means independent of said fluid for transmitting heat from said source of heat to the side of said oven adjacent to said source.
4. In a heating apparatus, a source of heat, a plurality of ovens disposed vertically with respect to each other, means forming a channel for the circulation of fluid in a closed circuit around said ovens and in heat exchange relation with said source of heat, said channel including a vertically extending leg in heat exchange relation with said source of heat and remote from said ovens, means independent of said fluid for transmitting heat from said source of heat to the side of said oven adjacent to said source, and means for preventing the introduction of fluid into said vertical leg at any intermediate point above the lower end thereof.

NILS AUGUST IVAN HALLSTRÖM.
